(No Model.)

A. W. ROBINSON.
FRICTION CLUTCH.

No. 465,536.

Patented Dec. 22, 1891.

UNITED STATES PATENT OFFICE.

ARTHUR W. ROBINSON, OF BUCYRUS, OHIO.

FRICITION-CLUTCH.

SPECIFICATION forming part of Letters Patent No. 465,536, dated December 22, 1891.

Application filed September 24, 1891. Serial No. 406,748. (No model.)

To all whom it may concern:

Be it known that I, ARTHUR W. ROBINSON, of Bucyrus, in the county of Crawford, State of Ohio, have invented certain new and useful 5 Improvements in Friction-Clutches Operated by Steam; and I do hereby declare that the following is a full, clear, and exact description of the same, reference being made to the accompanying drawings, in which—

10 Figure 1 is a longitudinal vertical section showing the arrangement of the parts as mounted on a shaft. Fig. 2 is an end view of the same, the shaft and sliding bar being sectioned on the line of the front of the connecting-bar. Fig. 3 is a detail end view showing 15 the parts employed for transmitting the motion, as hereinafter described, the sliding bar being cross-sectioned on a line at the front of the connecting-bar. Fig. 4 is a detail of the 20 parts shown in Fig. 3, taken at right angles thereto.

The first part of my invention relates to the means employed to convert motion along the axis of the shaft into rectilinear motion at right angles to the axis of the shaft or radially to a wheel mounted thereon, for the purpose of operating the friction-belt in such manner that the parts required to produce the end motion along the axis of the 25 shaft shall not occupy any extra space thereon, as is ordinarily the case, and also in such manner that I may employ a pair of toggles to operate the friction-belt.

The second part of my invention relates to 30 the manner of arranging a pair of toggles upon the rim of the wheel in such manner that the power applied to them is substantially uniform throughout the operation, while the resistance of the belt increases as it is applied.

In the drawings, A is the shaft upon which the entire apparatus is mounted.

B is a bearing for the support of one end of the shaft, the other end not being shown.

45 C is a hole extending through the center of the shaft for the purpose of containing the sliding bar D.

E is a spur-wheel or a pulley keyed upon the shaft, and to which the power is applied 50 by means of a pinion engaging with it or in any other suitable way.

In the drawings a portion only of the teeth

of the spur-wheel E are shown. At or near the rim of the spur-wheel E are three lugs F G H, having holes through them for the reception of steel pins or axes, upon which certain parts are pivoted or mounted, as herein-after explained.

K and L are two toggle-arms.

K is fulcrumed to the lug F at one end, and at the other it is fulcrumed at K' to the toggle-arm L, and the other end of the arm L is fulcrumed to a crank-pin L', which is upon a crank L², fast to a shaft or pin H', as herein-after explained.

J is a flat bar, preferably of steel, having parallel grooves or slots J' cut upon both sides of it at a suitable angle, (preferably about thirty degrees,) these being shown more fully in Figs. 3 and 4. The bar J passes through the hub of wheel E and the shaft A in openings provided for the purpose, and also through the center of the bar D, which is made in two recessed parts for the purpose of receiving it. They are firmly bolted together by bolts D', 75 the heads whereof are countersunk. The interior surfaces of the bar D where the bar J passes through it are also grooved or provided with longitudinally-running lands D², made to fit the grooves in the bar J, and of course they run on the same angle, and both the bar D and the bar J are confined within their respective holes, so that they can slide freely therein in the direction of their length, but not otherwise, the one at right angles to 80 the other. Therefore endwise movement of the sliding bar D will, owing to the bearing of the sides of the groove J' against the sides of the lands D², cause a lateral projection or retraction of the connecting-bar J, depending 85 on the direction of such movement.

P is a steam-cylinder which is fixed to the bed-frame B, being supported therefrom by suitable side brackets P'. The steam-cylinder P is controlled by a valve P², of any preferred construction, and may be operated in any usual and convenient manner. Its purpose is to give endwise movement to the bar D, and its piston-rod P³ is connected to the end of the bar D by a cross-head R in such a 95 way that the bar D can revolve with the shaft A, while the cylinder P, and consequently its piston-rod, does not so revolve. This is accomplished by making upon the end of the 100

bar D a circumferential groove P⁴, which fits into a corresponding recess in the cross-head R. The cross-head R is made in halves for the purpose of being placed in position, and it is preferably arranged to slide on any suitable ways, which may be made upon the brackets P'.

M is a drum of the apparatus to which the invention may be applied, having a housing 10 upon it, upon the periphery of which is a friction-surface O', upon which a friction-band O is adapted to take hold. The housing and drum are loose upon the shaft A, and the function of the apparatus is to connect 15 the wheel A with the housing by frictional contact, so that the power may be transmitted and applied and released at will. For this purpose the band O is connected at one end to a fixed point—as, for instance, a pin 20 in the lug G in the rim of the wheel E—and the other end of the band O is connected to a crank-arm Q, which is keyed upon the end of the steel pin or shaft H', passing through the hub H. This steel pin, as already stated, has 25 upon its opposite end a short crank-arm L', to which the toggle L is connected. The upper end of the connecting-bar J is fulcrumed to the toggle K at K². In this way it will be seen that by the movement of the bar J the 30 position of the toggles K and L are changed, so that they produce a tension on the end of the band O through the medium of the short lever arms on the pin H', before mentioned. The band O is preferably lined with wooden 35 blocks S, which form a better bearing-surface than the metal and which are also slightly elastic. It will be understood that as the toggles K and L are acted upon by the bar J and caused to come nearly in line with each other 40 that the power of the end-thrust will be greatly increased without requiring a corresponding increase of power applied by the bar J, and, furthermore, that when the toggles are in line with each other that they have 45 reached their maximum end-thrust and have no tendency to collapse and release the band, because they are on the dead-center.

The action of the apparatus will now be clearly understood, and is as follows: When 50 it is desired to apply friction, steam is admitted to the outer end of cylinder P, which creates an end movement of the piston, and, through the piston-rod, of the bar D. Through the medium of the grooves and lands at the 55 intersecting portions of the bars D and J the end movement of bar D is converted into a rectangular motion of bar J at right angles to the bar D, as before described, the interlocking parts sliding upon each other, as in a 60 screw-thread. The thrust of the bar J is applied to the toggles K and L, and consequently, owing to the rocking of the pin or shaft H', and consequent movement of the crank-arm Q, tightens the band O, as already described, 65 and creates a powerful frictional contact upon the exterior of the friction-surface O'. In a similar manner when it is desired to re-

lease the friction steam is admitted into the opposite end of the cylinder P and the reverse action takes place, the housing N and 70 any parts that may be attached to it being then free to revolve upon the shaft independent of the gear E.

It will be obvious to those who are familiar with this art that many alterations may be 75 made in the details of construction and still the essentials of my invention be employed. I therefore do not limit myself to the details.

I do not broadly claim the friction-clutch of the band type, as such is old; neither do I 80 claim the combination of the housing end loose upon the shaft in connection with the spur-wheel E, for I am aware that they are not new; but

What I claim as my invention, and desire 85 to secure by Letters Patent, is—

1. In a steam-operated friction-clutch, the combination, with a shaft upon which clutch mechanism is mounted and a steam-cylinder, piston, and piston-rod, of intermediate operating mechanism comprising two sliding bars at right angles to each other and respectively connected with said piston-rod and said clutch mechanism proper and working, respectively, within and at right angles through 90 but independently of said shaft and having an oblique sliding friction connection the one with the other, for the purpose set forth.

2. In a steam-operated friction-clutch, the combination, with a shaft upon which the 100 clutch mechanism proper is mounted, a steam-cylinder, and a piston and piston-rod, of intermediate operating mechanism comprising a sliding bar connected at one end with the piston-rod and fitting within the said shaft, 105 which is hollowed to receive it, another bar having one end connected to the clutch mechanism proper and the other end extending through said shaft and sliding bar, and an oblique tongue-and-groove sliding connection 110 between said bars, as set forth.

3. The combination of a clutch mechanism proper, a shaft, a steam-cylinder, a sliding bar actuated thereby and having end motion within the hollow of said shaft, said bar having 115 formed upon it grooves and lands at a suitable angle relative to the axis of the bar, and another bar also grooved to fit between the two halves of the bar D at about right angles with the same, substantially as and for 120 the purposes set forth.

4. The combination of a steam-actuated sliding bar located within a shaft and provided with inclined lands, a bar arranged at right angles to the sliding bar, held against 125 movement lengthwise of the shaft and provided with grooves and lands and attached at one end to toggles which are fastened to a wheel mounted upon the shaft and by which the friction device is actuated, for the purposes set forth.

5. The combination of two bars placed cross-wise of each other and having interlocking surfaces arranged at angles to their respect-

ive axes, and a pair of toggles actuated by the bars, a friction device connected with the toggles, and means whereby the bars are held in position relative to each other and are given movement relative to each other, for the purposes set forth.

6. The combination, with a hollow shaft, a steam-cylinder, and a clutch mechanism proper, of a grooved bar connected to or forming part of the piston-rod of the cylinder located within the hollow shaft, and another

grooved bar passing through slots in the shaft, the grooves upon the said bars engaging with each other at right angles within the shaft, substantially as set forth.

15

Signed at Bucyrus, in the county of Crawford and State of Ohio, this 15th day of August, A. D. 1891.

ARTHUR W. ROBINSON.
